ELECTRIC SWITCH

Morris Roteman, Los Angeles, Calif.

Application July 13, 1953, Serial No. 367,607

5 Claims. (Cl. 200—168)

This invention relates to electrical fittings for mounting push button switches and the like to a plastered or stuccoed wall of a building. Although the invention perhaps finds its greatest usefulness in connection with electrical fittings as installed on structural framing surfaced with a hard layer such as stucco, it is not necessarily limited to that use as will be hereinafter seen.

Currently such fittings usually consist of a single plate bearing a push button switch closing the circuit of some house-service means, such as door chimes or the like. The switch is generally mounted in a central aperture in the single plate which is formed with apertures for passing screws for mounting the plate to the wall. To securely anchor the single plate to the wall, it is preferred that the mounting screws be anchored in a stud disposed behind the stucco layer. The mounting of such fittings to stucco walls by screws driven into the blind stud entails laborious groping or probing with the screws to locate the stucco covered stud. Even the practice of sounding for the stud by striking the wall with a hammer or the like seldom locates the stud accurately.

Aside from the time consuming nature of this practice, there was always the likelihood especially when long brass screws are used, of the same being stripped or burred as they are driven through the stucco layer. In some instances several screws are damaged beyond use before the blind stud is located and the necessary mounting screws properly driven home into the stud.

If the plate is mounted to the stucco wall by relatively short screws merely anchored in the stucco itself, they soon loosen and the plate fails to remain in place. Further the loosened plate permits entrance of rain into the switch cavity in the wall to produce short-circuiting and deterioration of the switch and the terminal leads connected thereto.

In order to ameliorate these and other disadvantages of prior practice, this invention provides a fitting which obviates the employment of screws as both "probes" and fasteners and by the use of simple driven fasteners, such as nails together with a base plate through which they may be driven at any angle necessary to "find" the stud, provides a mounting element to which the cover plate can be easily secured. The present invention thus provides a fixture adapted for ready attachment to a blind stud or the like through a hard surfaced layer of substantially any thickness without repetitive operations and without loss or damage to the mounting screws.

More specifically, the illustrated embodiment of the fixture of the present invention comprises a pair of oblong plates, a base plate and a cover plate, which are adapted to be arranged in mutually facewise confronting relationship and in facewise spaced disposition.

The base plate is provided with a pair of slots lying adjacent opposite edges thereof and which extend breadthwise of the plate for receiving nails or the like which are to be driven through the stucco and into the stud. A pair of tapped apertures are also provided in this plate

2

and are adapted to receive relatively short mounting screws passed through apertures formed in the cover plate which also forms a supporting container for the switch. The container formed by the cover plate can be drawn tightly against the stucco layer and acts to seal the switch, its binding post, and the conductor terminals from the weather.

Other features and advantages of the present invention will be hereinafter apparent from the following description, particularly when taken in connection with the accompanying drawing, in which—

Figure 1 is a fragmentary, vertical section through a stuccoed outer wall of a house, taken before the installation of the present fixture and showing the electrical leads "rough-wired" alongside a stud (shown in side view or side elevation) and with their terminals held temporarily in place in the aperture in the stucco by means of a nail to be removed by the installer of the fixture of the present invention.

Figure 2 is a fragmentary horizontal section of this wall with the "rough-wiring" nail removed and with the wiring connected to the novel fixture, the latter in turn being firmly fixed to the stud;

Figure 3 is a section taken along line 3—3 of Figure 2; and

Figure 4 is an expanded perspective view of the fixture with one of the major parts fixed to a fragment of the wall, and omitting the two plate-uniting screws.

The fitting of the present invention is particularly useful in mounting a switch to a stucco wall such as illustrated in Figure 1 of the drawing. The figure depicts a wall of a building constituted in part by a wooden stud or riser 10 and a surfacing laminate that includes a stucco layer 11 extending between adjacent studs. The material forming the layer 11, when applied, is formed with a recess or depression 12 intended to receive the switch body to be mounted to the wall.

In the usual building practice today, and before the layer 11 is applied, electricians, in rough wiring the building, run leads 13 up alongside the stud 10 and the terminal ends 14 thereof are wrapped around a nail 15 driven into the stud 10. The nail, removed at the time the switch is mounted, is used merely as a temporary anchoring and locating means for the terminals 14 to facilitate the mounting of the switch subsequent to the application of the stucco layer.

In some cases, the workmen applying the stucco layer dislodge the nail 15 from the stud so that the exact location of the stud is not known at the time the switch is applied to the finished stucco layer. In other instances, although the nail 15 remains in place after the layer of stucco is applied, it is loosened or bent and fails to accurately locate the position of the blind stud. Either one of these contingencies complicates the mounting of the switch, particularly if the switch is to be securely mounted by anchoring the mounting screws into the blind stud. This is so for the workman installing the switch is forced to probe for the stud before the switch can be mounted securely to the wall, as hereinbefore explained.

The present invention obviates these difficulties for the terminals 14 of the leads 13 can be attached to a circuit closing switch device carried by one of the present novel fixtures and the latter in turn quickly and easily anchored to the blind stud through the layer of hard stucco.

To the latter end, the fixture of the present invention comprises an inner or base plate 16 of rectangular form adapted to fit facewise against the outer face of the stucco layer 11 overlying the depression 12 formed in the latter. The plate 16 is essentially a fixture positioning and cover supporting member and to these ends is provided with a pair of elongate apertures or slots 17 extending breadth-

wise of the plate, as shown in Figure 4, and disposed preferably near the adjacent short edges of the plate. The walls of each of the slots or apertures 17 are smooth and freely pass therethrough at least one nail 18 or other simple percussion driven fastener. As the slots 17 are of a size sufficient to each pass a relatively large nail, the plate 16 is easily and quickly mounted in position on the surface of the wall. This is so for the nails used can be angled towards the stud and driven home thereto, usually at the first attempt, but if they do not strike the stud, they can be easily removed without damage to them or the stucco and redriven at another angle or other positions along the slots to securely mount the plate 16 properly in position over the recess 12.

The plate 16 is provided with a centrally formed aperture 19 adapted to pass a push button switch 20 carried by an outer or facing plate 21. The switch 20 can be mounted to the plate 21 in any manner desired and may, as herein shown, be merely press fitted into the opening 22 formed in the plate 21. In the embodiment of the invention herein shown, the aperture 19 and the mounting opening 22 are each illustrated as circular, but as should be understood the size and shape thereof depends on the size and shape of the switch 20 mounted to the cover plate 21. It can be mentioned here, as best seen in Figure 3, that the defining edges of the aperture 19 also act to support the inner end of the switch 20. The switch 20 projects into the recess 12 formed in the layer 11 in which the terminals of leads 13 are disposed and which are to be connected to the switch.

The cover plate 21 is just slightly larger than the plate 16 and like plate 16 is also preferably elongate rectangular in planform. The plate 21 carries a peripheral flange 23 directed inwardly toward the periphery of plate 16 and this flange presents an opening substantially the same size and shape as plate 16. The plate 21 with its internal flange 23, as best seen in Figure 3, presents a box-like container for receiving the plate 16. Thus the flange 23, as shown in Figure 3, engages about the peripheral edge of the plate 16 and abuts against the outer face of the stucco layer 11.

Plate 21 is provided with a pair of apertures 24 so arranged therein to register with tapped apertures 25 formed in the plate 16 when the two plates are assembled as shown in Figure 3. The apertures 24 are preferably countersunk to receive the heads of mounting screws 26, the shanks of which are threadedly engaged in the apertures 25 of the plate 16. Thus it will be seen that the screws 26 are used to secure the cover plate 21 to the base plate 16 and to pressurely urge the edge face of the flange 23 tightly against the outer surface of the stucco layer 11.

Before the screws 26 are tightened to mount the plate 21, the terminal ends 14 of the conductors 13 are cleaned and attached in a conventional manner to binding posts 27 of the switch 20. Once this connection has been established, the plate 21 is mounted to the base plate 16 through the screws 26, as above described.

It will now be seen that the plate 21 actually forms a box-like receptacle which carries and encloses all but the actuator button 28 of the switch 20. Thus the switch and particularly its binding posts and the terminal ends 14 of the leads 13 connected thereto are protected against deterioration from the weather. As the screws 26, when tightened, pressurely urge the flange 23 tightly against the stucco wall, a very efficient weather seal is provided which will prevent rain running downwardly over the outer surface of the wall 11 from entering the switch housing.

It should now be seen that the fitting of the present invention provides means for mounting a house service switch to a stucco or plastered wall without the difficulties heretofore experienced. The fitting, furthermore, as above explained, insures a longer service life for the switch mounted thereby as well as the terminal leads of the circuit controlled by the switch.

Although the now preferred embodiment of the present invention has been shown and described herein, it is to be understood that the invention is not to be limited thereto, for it is susceptible to changes in form and detail within the scope of the appended claims.

I claim:

1. A device of the type described to be mounted at an external recess in a structural wall having an outer layer of stucco over a frame including vertical studs, comprising: a rectangular plate member wider and longer than said recess, said plate member having a relatively large centrally located opening therein and a transverse elongate slot formed adjacent each of the upper and lower ends of the plate centrally thereof, said slots passing nails at the required angle of drive to extend through said outer layer into one of said studs thereby to securely fix said plate facewise to said wall; a rectangular cover element including an inturned marginal flange for enclosing said plate member adjacent its four edges; means for securing said cover element to said plate member with the flange of the former engaging said wall; and a switch, including a body element and an actuator element, carried by said cover element, said switch body retractably extending into said centrally located opening of the plate member with the actuator member accessible for manual operation exteriorly of said device.

2. A device of the type described to be mounted at an external recess in a structural wall having an outer layer of stucco over a frame including vertical studs, comprising: a plate member having a relatively large centrally located opening therein with transverse elongate slots formed on opposite sides of said opening and adjacent each of the upper and lower ends of said plate, said slots passing nails at the required angle of drive to extend through said outer layer into one of said studs thereby to fix said plate facewise to said wall; a rectangular cover element including a marginal flange for enclosing said plate member; means for securing said cover element to said plate member and pressurely engaging the edge face of said flange against said wall surface adjacent the marginal edges of said plate; and a switch including an actuator button mounted to said cover element and extending into said centrally located opening of said plate member and partially supported by the defining edges thereof.

3. A device of the type described to be mounted at an external recess in a structural wall having an outer layer of stucco over a frame including vertical studs, comprising: a plate member wider and longer than said recess, said plate member having a relatively large centrally located opening therein and a transverse elongate slot formed adjacent each of the upper and lower ends thereof, said slots passing nails at the required angle of drive to extend through said outer layer into one of said studs thereby to fix said plate facewise to said wall; a box-like cover element of a size and shape for enclosing said plate member; means securing said cover element about said plate member including means for mounting said cover member to said plate member, whereby the former is affixed to said wall; and a switch having walls completely enclosing the mechanism of the switch from the sides and back thereof, said switch including an actuator button, said switch being mounted to said cover element and extending into said centrally located opening of said plate member and partially supported by the defining edges thereof.

4. A device of the type described to be mounted at an external recess in a structural wall having an outer layer of stucco over a frame including vertical studs, comprising: a rectangular plate member having a relatively large centrally located opening therein and a transverse elongate slot formed adjacent each of the upper and lower ends thereof, said slots passing nails at the required angle of drive to extend through said outer layer into one of said studs thereby to fix said plate facewise to said wall; a rectangular cover element including a marginal flange

for enclosing said plate member; said cover element being formed with spaced apertures registering with tapped openings formed in said plate; mounting screws passed through said apertures and threadedly engaged in said tapped opening for securing said cover element to said plate member; and a switch, including an actuator button, mounted to said cover element and extending into said centrally located opening of said plate member and partially supported by the defining edges thereof, said mounting screws adapted to draw the edge face of said flange against the contiguous wall surface to provide a weather seal.

5. A device as set forth in claim 1 in which said plate

has tapped openings and said cover has apertures registering therewith; and which includes mounting screws passed through said aperture and threadedly engaged in said tapped openings for securing said cover to the plate member and for drawing the cover adjustably into pressure contact in said outer layer of stucco.
